B. H. Jenks.

Cams for Looms.

N° 63,055.

Patented May 19, 1867.

United States Patent Office.

BARTON H. JENKS, OF BRIDESBURG, PENNSYLVANIA.

Letters Patent No. 63,055, dated March 19, 1867.

IMPROVEMENT IN TREADLE-CAM FOR LOOMS.

The Schedule referred to in these Letters Patent and making part of the same.

TO ALL WHOM IT MAY CONCERN:

Be it known that I, BARTON H. JENKS, of Bridesburg, in the county of Philadelphia, and State of Pennsylvania, have invented an Improvement in Cams for Operating Treadles in Looms for Tweeling; and I do hereby declare that the following is a full, clear, and exact description thereof, reference being had to the accompanying drawings, making a part of this specification, in which—

Figure 1 is a horizontal section of a loom taken above the cam-shaft, showing my improved cam applied to it.

Figure 2 is an enlarged view of one of the improved grooved cams.

Figure 3 is an end view of the same.

Figure 4 shows in a cross-section the two parts of the grooved cam detached.

Similar letters of reference indicate corresponding parts in the several figures.

This invention relates to an improvement on looms which are designed for weaving twilled fabrics, and in which reciprocating cams are employed as described in the patent of Richard Garsed, which was granted on the 20th day of July, 1846, and extended on the 18th day of July, 1860, and subsequently assigned to me. In this loom of Garsed the cams are placed upon the middle of the cam-shaft between the intermediate bearings thereof. This cam-shaft is also employed for driving other parts of the loom besides the treadles, such as the pick motion, thread-protector motion, box motion, &c. When a change was necessary from one grooved hub or cam to another, having a greater or less number of grooves, all the said connections were displaced, the cams removed from the shaft by sliding them off endwise, the new cams substituted for those last in use, and adjusted in proper position and relation to the treadles, after which the cams and dogs for actuating other parts of the loom above referred to were adjusted upon the shaft in proper time and relation to each other, requiring considerable labor, time, and skill.

The object of my invention and improvement is to so construct the grooved hubs, sleeves, or cams which actuate the treadle-cams, that all the required changes can be made for moving a greater or less number of treadles, or for moving a given number of treadles in any required order, by simply removing those portions of said hubs or sleeves which produce said changes, and without the necessity of removing the cam-shaft from its bearings or disturbing such parts as may be connected to this shaft, as will be hereinafter described.

To enable others skilled in the art to understand my invention, I will describe its construction and operation.

In the accompanying drawings A represents the cam-shaft, having the picker cams *a a* secured permanently to it in the usual manner, and C C are the harness cams for acting upon the treadles *b b*, of which six are represented, the number required for three sets of harness for weaving three-twilled cloth. The cams C C are secured in a suitable manner to cylindrical hubs, D D, that slide freely on the shaft A in an endwise direction, and at the same time turn with it by means of a feather or key tenon, *c*. In fig. 1 the hubs D D are each represented with three grooves, at equal distances apart, passing around its periphery. On one side of each hub the straight portions of the grooves run into other grooves passing obliquely over the surface of the hub so as to intersect each other, as shown, in two directions. F F represent two horizontal studs projecting from the frame G, and on the inner end of each stud turns a feather, *d*, which fits the grooves in the hubs D freely, and which is made of such length, with the ends reduced in thickness, as to pass the junctions of the diagonal portions of the grooves where they cross each other. When the diagonal portions of the grooves pass the feathers, the smallest diameter of the cams C C pass the treadle, at which time the cam and treadles are not in contact, and therefore the former are free to slide on the shaft A without touching the treadles. By increasing the number of grooves in each hub any desired number of treadles can be operated.

Having described the manner of operating the treadles of looms for weaving twilled fabrics, I will now describe my improved mode of constructing the grooved hubs or cams D D, which give the endwise movements to the treadle cams C C, so that the required changes can be made without removing the main shaft A from its bearings. The grooved hub shown in figs. 2, 3, 4, and 5 consists of two parts or segments, D and D', which form a complete cylinder when put together, as shown in figs. 2 and 3. The largest segment, D, is permanently, but loosely, applied on the cam-shaft A, and is secured rigidly to the cam C, which works the treadles. The smaller section or segment D' is constructed with lips or tenons upon its ends, which fit snugly into corresponding recesses formed in the portion D, as shown, and by means of screws this segment D' is

firmly secured to the segment D, thus forming a perfect cylinder. That portion of the hub which is permanently attached to the shaft A, but allowed to slide endwise thereon, has straight and parallel grooves formed in its periphery, which are lettered $g\ g\ g$, and that portion of the hub which is removable has oblique or diagonal grooves, $g'\ g', g'$, formed in its periphery, which grooves are equal in width to the straight or parallel grooves in the portion D, and form, together, channels for receiving the feather d , and causing the hub and its cam C to receive an endwise reciprocating movement on the shaft A when the latter is turned. The segment D', which has the oblique intersecting grooves formed in it, is made removable from the segment D for the purpose of employing another segment of the same size and shape, when it is desired to employ a greater or less number of grooves and a greater or less number of treads. Therefore, when a change is required, it is only necessary to remove the diagonally grooved segment D' and substitute a different one, which will give the required change.

Having described my invention, what I claim as new, and desire to secure by Letters Patent, is—

Constructing the grooved hub of a treadle-cam, C, of two parts, substantially in the manner and for the purpose described.

BARTON H. JENKS.
